UNITED STATES PATENT OFFICE.

FRED W. POWERS, OF CHICAGO, ILLINOIS.

PILOT BURNER

Application filed January 26, 1922. Serial No. 531,962.

To all whom it may concern:

Be it known that I, FRED W. POWERS, a citizen of the United States, and resident of Chicago, in the county of Cook and State of Illinois, have invented certain new and useful Improvements in a Pilot Burner, of which the following is a specification.

My invention relates to oil and gas burners and particularly to devices of the sort with which a pilot light or burner is employed to effect re-ignition in event of extinguishment.

In the devices such as described with which fuel oil is employed, it is customary to provide a pilot light in which gas is used, the ordinary method involving the maintenance of a small gas flame or jet. Such a burner is wasteful in its consumption of gas and is very easily extinguished. If it is extinguished the fuel oil is likely to be discharged into the heater without being ignited.

In the device of my invention I accomplish two objects, first, the provision of a burner which is not readily extinguished and which will be instantly re-ignited in effect of such an occurrence and second, the provision of a thermostatic control associated with the pilot burner and acting to interrupt the supply of fuel to the main burner in the event of the necessity therefor.

The pilot burner of my invention is preferably of the Bunsen type, which produces a hotter flame with a reduced quantity of gas. This type of burner also eliminates the production of soot. To effect re-ignition in the event of the accidental extinguishing of the pilot, I provide at a point adjacent to the outlet from the pilot burner, a refractory element adapted to be maintained in an incandescent or red hot state. Inasmuch as the pilot burner is usually extinguished by reason of an explosive puff in the firebox the burner will be immediately re-ignited due to the contact of the gas with the incandescent re-ignition point.

The thermostatic element is preferably in the form of a tube clamped to the pilot burner and communicating by a flexible tube with a motor diaphragm which operates a fuel shutoff valve which is normally closed except when held open by the thermostatic pressure. A liquid having a low boiling point is confined in the thermostatic tube and will serve to maintain the valve in open position when the burner is in oper-

ation. Reversely when the pilot is extinguished the reduced thermostatic pressure will permit the closing of the valve by the spring and the interruption of the supply of fuel to the main burner.

My invention will be more readily understood by reference to the accompanying drawing, in which—

The figure is an elevation partly in section showing an arrangement such as conceived by me.

In the drawing, the device is shown projecting through a wall 10 of a furnace or a heater, a fuel oil burner 11 serving to provide the heating flame. Fuel is supplied to the burner by means of the pipe 12 and air by means of the pipe 13. A shutoff valve 14 is provided in the oil supply line, this including a valve member 15 normally held against its seat by means of a spring 17 held in position by a closing cap 18. A stem 19 projects downwardly from the valve member and into a small diaphragm 20 which serves to seal the valve and avoids the necessity of packing the stem 19. A motor diaphragm or disk 21 abuts the sealing diaphragm 20, the parts being held within a yoke 22 secured to the valve fitting 14. An armored tube connects the interior of the motor diaphragm 21 with a rigid tube 24 which acts as a thermostatic bulb and is held by means of clamp 25 against the pilot burner 26 which also projects into the furnace beneath the main burner. The pilot burner is preferably of the Bunsen type and is provided with a transverse screen 27 adapted to prevent back-firing. Gas is supplied to the burner through the pipe 28.

Located immediately adjacent to the opening in the pilot burner is a refractory wire 29 of such size and composition as to enable it to withstand the heat and be maintained at incandescence or at least at such temperature as will effect re-ignition of the gas in event of a puff in the furnace which would serve to extinguish the pilot burner.

The arrangement is such that in event of the extinguishment of the pilot burner, the temperature thereof will be reduced and the thermostatic liquid within the bulb 24 will be condensed thus permitting the spring 17 to close the fuel valve 15. This will serve to prevent the escape of unburned fuel into the heater.

Obviously the construction is capable of

modification and I do not wish to be limited except as indicated in the appended claims.

I claim:

- 5 1. In regulating apparatus, the combination of a main burner, a pilot burner, a valve for controlling the supply of fuel to the main burner, a thermostatic tube lying adjacent to said pilot burner, a bellows for actuating said valve, a flexible tube connecting said thermostatic tube and said bellows, the said thermostat acting through said bellows to directly effect the closing of said valve upon continued extinguishment of the pilot burner.
- 10 2. In regulating apparatus, the combination of a main burner, a pilot burner, a valve for controlling the supply of fuel to the main burner, a thermostatic tube lying adjacent to said pilot burner, a bellows for actuating said valve, a flexible tube connecting said thermostatic tube and said bellows, the said thermostat acting to directly close said valve upon continued extinguishment of said pilot burner.

2. In regulating apparatus, the combination of a main burner, a pilot burner, a valve for controlling the supply of fuel to the main burner, a thermostatic tube lying adjacent to said pilot burner, a bellows for actuating said valve, a flexible tube connecting said thermostatic tube and said bellows, the said thermostat acting through said bellows to directly effect the closing of said valve upon continued extinguishment of the pilot burner.

tion of a main burner, a pilot burner, a valve for controlling the supply of fuel to the main burner, a thermostatic tube lying adjacent to said pilot burner, a bellows for actuating said valve, a flexible tube connecting said thermostatic tube and said bellows, the said thermostat acting through said bellows to directly effect the closing of said valve upon continued extinguishment of the pilot burner.

Signed at Chicago, Illinois, this 23rd day 25 of January, 1922.

FRED W. POWERS.
